UNITED STATES PATENT OFFICE.

ARTHUR J. BENNETT, OF CAMBRIDGE, OHIO.

DESIGN FOR A SMOKER'S TRAY.

Application filed January 23, 1926. Serial No. 16,237. Term of patent 7 years.

To all whom it may concern:

Be it known that I, ARTHUR J. BENNETT, a citizen of the United States of America, and resident of Cambridge, county of Guernsey, and State of Ohio, have invented a new, original, and ornamental Design for a Smoker's Tray, of which the following is a specification, reference being had to the accompanying drawings, in which—

I claim:

The ornamental design for a smoker's tray, as shown.

ARTHUR J. BENNETT.
